Primary Examiner—Daniel Bui*Assistant Examiner*—Elizabeth J Oswecki(74) *Attorney, Agent, or Firm*—Cynthia R. Miller(57) **CLAIM**

The ornamental design for a cosmetic bottle, substantially as shown and described.

DESCRIPTION

FIG. 1 is a top, front and right side perspective view showing our new design for a cosmetic bottle;

FIG. 2 is a front elevation view of the cosmetic bottle shown in FIG. 1;

FIG. 3 a right side elevation view of the cosmetic bottle shown in FIG. 1, the left side elevation view being identical thereto;

FIG. 4 is a rear elevation view of the cosmetic bottle shown in FIG. 1;

FIG. 5 is a top plan view of the cosmetic bottle shown in FIG. 1; and,

FIG. 6 is a bottom plan view of the cosmetic bottle shown in FIG. 1.

The broken lines shown in the figures are for illustrative purposes only and form no part of the claimed design.
